DESIGN FOR A COSTUME JEWELRY PIN OR SIMILAR ARTICLE

Frederick Gallo, Mineola, N. Y., assignor to Karl Strotkemper and Salvatore Riolo

Application May 18, 1946, Serial No. 129,827

Term of patent 14 years

(Cl. D45—19)

To all whom it may concern:

Be it known that I, Frederick Gallo, a citizen of the United States of America, and a resident of Mineola, county of Nassau, and State of New York, have invented a new, original, and ornamental Design for Costume Jewelry Pin or Similar Article, of which the following is a specification, reference being had to the accompanying drawing, forming a part thereof in which

Fig. 2 is a bottom plan view thereof; and

Fig. 3 is a vertical cross sectional view thereof taken on the line 3—3 of Figure 1.

I claim:

The ornamental design for a costume jewelry pin or similar article, as shown.

FREDERICK GALLO.
